UNITED STATES PATENT OFFICE.

RICHARD J. VICKERY AND JOHN J. DINSMORE, OF CLARK, SOUTH DAKOTA.

PLOW.

No. 853,047.

Specification of Letters Patent.

Patented May 7, 1907.

Application filed February 9, 1907. Serial No. 366,536.

To all whom it may concern:

Be it known that we, RICHARD J. VICKERY and JOHN J. DINSMORE, citizens of the United States, and residents of Clark, in the county of Clark and State of South Dakota, have invented certain new and useful Improvements in Plows, of which the following is a specification.

Our invention is an improvement in plows, and particularly in plows arranged in gangs; and the invention consists in certain novel constructions and combinations of parts as will be hereinafter described and claimed.

In the drawings Figure 1 is a top plan view partly broken away in section and parts being removed of an implement embodying our invention. Fig. 2 is a side view thereof the plows proper and their beams and adjusting devices being removed. Fig. 3 is a front elevation of the framing of the plow and its supporting means. Fig. 4 is a perspective view of the frame and its supporting beams. Fig. 5 is a detail sectional elevation illustrating one of the plow beams and the devices immediately connected therewith, and Fig. 6 is a sectional elevation on about line 6—6 of Fig. 5, and Fig. 7 is a detail plan view showing a part of the diagonal main beam and one of the swinging braces and a portion of the step-shape plate.

In carrying out our invention we provide a frame as shown in Figs. 3 and 4 and comprising a front beam A, side beams B and C, the beam B extending to a considerable distance in rear of the beam C, and a diagonal main beam D secured at its rear end upon the side beam B near the rear end thereof and at its front end upon the side beam C near the front end of said side beam C and directly in rear of the beam A, which beam A extends transversely across the frame at the front end thereof and is secured at its opposite ends upon the beams B and C, as shown in Figs. 3 and 4 of the drawings. The beams A, B, C and D are of structural metal and the upper faces of the beams A and D are in the same plane and form a base upon which a platform E is secured. This platform extends substantially over the entire frame and is preferably made of 2x2 timbers, set slightly apart, as shown in Fig. 3. The operator may stand upon this platform and manipulate the several plows independently in the manner presently described.

55 A front draft bar F extends transversely across the frame below the beam A and is

provided with openings F' through which the draft rods G extend, as shown in Fig. 5, said draft rods also extending through a diagonally disposed swinging spacing bar H loose at both ends and extending below the main beam D and perforated at H' for the draft rods G, see Figs. 4 and 5. These bars F and H operate to maintain the draft rods preferably spaced apart in the operation of the machine.

The main frame is supported by the furrow wheel I and the land side wheels J whose forked arms I' and J' are provided with upwardly extending shafts I² and J² journaled in bearings mounted on the main frame. The wheel I runs in a furrow and may be adjusted up and down and held at any desired height by means of the lever I³ arranged as best shown in Fig. 2.

The beam D is channeled in its rear and front faces, the rear channel affording a secure seat in which we fasten by bolts or rivets the step shaped bar L having the lateral wings L' and the longitudinal wings L², the latter bracing the outer ends of the lateral wings L', as shown in Figs. 1 and 4 and the plate L being secured to the beam D of the main frame at the juncture of its said wings L' and L², as shown.

By the described construction we provide at intervals along the diagonal main beam laterally projecting plates or bars to which are pivoted the swinging braces M which connect with and operate to steady the rear ends of the plow beams in the use of the invention. These swinging braces M are formed as best shown in Figs. 1 and 6 with a shaft M' journaled in eyes M² on the plates or bars L' and with the side bars M³ which extend from the ends of the shaft M' and converge toward their rear ends where they are pivoted at M⁴ to a post N' mounted on the plow beam N near its rear end. By this construction the swinging brace steadies the rear end of the plow beam and at the same time does not interfere with the raising and lowering of said beam in the operation of the implement.

The plow beam N has at its front end the clevis N² which is connected by the link or clevis N³ with the draft rod G. The gage wheel O, colter P and plow share Q are connected with the beam. The plow share Q is fixed to the standard Q' which latter is pivoted at its upper end Q² to the beam N and is held normally in place by a strut.

brace Q^3 which is secured by a wooden or other break pin Q^4 to the beam N .

The plow beams are each suspended by the front and rear hangers R and S , preferably in the form of chains from the bell crank levers R' and S' which latter are connected by the rods R^2 and S^2 with the hand lever T , the connection with the front and rear bell crank levers R' and S' being effected on opposite sides of and respectively below and above the pivot T' of the operating lever, and the latter having a detent T^2 engaging a rack T^3 whereby the beam may be held elevated to any desired extent. Mani-

festly, by the operation of the lever T , the entire plow beam and the parts connected therewith may be elevated, but the front end of the beam will be raised allowing the plow to run out of the ground gradually.

20 In operation the implement may be connected with any suitable form of traction engine to which end we secure to the front side of the draft bar F a triangular wooden draft frame U connected at U' to the said draft bar and having a central draw bar U^2 of iron extending across the frame U at the middle thereof and provided at its front projecting end with an eye U^3 which may be coupled in any desired manner with the traction engine or other suitable draft apparatus.

We claim—

1. The combination substantially as herein described with the main frame having the opposite side beams, the transverse front beam secured upon the side beams and the diagonal main beam secured upon the opposite side beams, the upper faces of the diagonal main beam and the front beam being in the same plane, the platform secured upon said beams, the wheels journaled to the side beams and adapted to support the main frame, a transverse draft bar at the front of the main frame and below the front beam and provided with perforations for the draft rods, the diagonal spacing bar arranged in rear of the front draft bar and perforated in alinement with the perforations in said front bar to receive draft rods, draft rods in the said perforations of the front draft beam and 40 spacing bar, the plow beams connected at their front ends to the rear ends of the draft rods, the step shaped plate secured to the rear side of the diagonal beam and having the lateral wings and the longitudinal wings 45 extending from the outer ends of the lateral wings to the diagonal beam, the swinging braces pivoted at their upper front ends to the respective lateral wings of the step shaped plate, connections between the rear ends of

the swinging braces and the plow beams, 60 hangers in connection with the front and rear ends of the plow beams, bell crank levers connected with said hangers, and operating levers connected with the bell crank levers to operate the same, substantially as set forth. 65

2. The combination substantially as described of the main frame having the diagonally disposed main beam and provided thereon with lateral plates or bars arranged in step-like form, swinging braces pivoted at their upper forward ends to their respective lateral plates or bars, plow beams connected with the rear swinging ends of the respective swinging braces, means for elevating the plow beams, and draft devices in connection with the said beams, substantially as set forth. 70

3. The combination of a main frame having a diagonal main beam, and a series of lateral beams or plates arranged in step form, 80 a series of plows corresponding to said lateral plates or beams, swinging braces connecting the said plows with their respective lateral beams or plates, and means supported on the main frame for raising and lowering the several plows independently, substantially as set forth. 85

4. The combination with the main frame having a diagonal main beam, a transverse draft bar at the front of the main frame, and a diagonal laterally swinging spacing bar in rear of said front bar and provided with perforations for draft rods, a series of plow beams in rear of said diagonal spacing bar, a series of draft rods extending through the spacing bar and connected with the front draft bar, and connections between the rear ends of the several draft rods and their respective plow beams, substantially as set forth. 90

5. The combination of the main frame having a front draft bar, a diagonal spacing bar in rear thereof and perforated for draft rods, and a diagonal main beam provided with lateral bars or plates in step form, plow beams below the several lateral bars or plates, swinging braces between the plow beams and said lateral bars or plates, means on the main frame for raising and lowering the several plow beams, draft rods extending through the spacing bar and connected with the front draft bar, and connections between the said draft rods and their respective plow beams, substantially as set forth. 100 105 110
